UNITED STATES PATENT OFFICE.

PAUL JUSCHKE, OF NEW YORK, N. Y.

POOL-BALL PLACER AND HOLDER.

SPECIFICATION forming part of Letters Patent No. 752,292, dated February 16, 1904.

Application filed October 23, 1903. Serial No. 178,192. (No model.)

To all whom it may concern:

Be it known that I, PAUL JUSCHKE, a citizen of the United States, residing at New York, in the county of New York and State of New York, have invented certain new and useful Improvements in Pool-Ball Placers and Holders, of which the following is a specification, such as will enable those skilled in the art to which it appertains to make and use the same.

The object of this invention is to provide an improved device for holding pool-balls and for placing the same in proper position on a pool-table without the necessity of sliding the ordinary triangular holder over the table, and thus injuring the cloth with which the table is covered, a further object being to provide a triangular holder for pool-balls in which the latter may be placed when they are taken from the pockets and from which the said balls may be deposited in their proper position on the table; and with these and other objects in view the invention consists in a device of the class specified, constructed as hereinafter described and claimed.

The invention is fully disclosed in the following specification, of which the accompanying drawings form a part, in which the separate parts of my improvement are designated by suitable reference characters in each of the views, and in which—

Figure 1 is a plan view of a device embodying my invention; Fig. 2, a cross-section on the line 2 2 of Fig. 1; Fig. 3, a view similar to Fig. 2, but showing the balls in a different position; and Fig. 4, a view of a detail of the construction.

In the practice of my invention I provide a triangular frame *a* of the same form as those usually employed in placing pool-balls in proper position on a table, and the said triangular frame is provided in opposite sides thereof with holes *a*², through which are passed fingers or rods *b*, connected by a handpiece *b*². The fingers or rods *b* are preferably triangular in cross-section, as shown in Figs. 2 and 3, and the holes in the sides of the frame *a* are similarly formed.

The handpiece *b*² is preferably provided with a flange member *b*³, by which it may be ma-

nipulated, and in practice the rods or fingers *b* are passed through the triangular frame *a*, and in Fig. 1 of the drawings that part of the device represented by the fingers or rods *b* and the handpiece *b*² is shown partially withdrawn in full lines.

In practice the fingers or rods *b* are passed entirely through the triangular frame *a* and the balls are collected and placed in said frame and rest on said fingers or rods, and when it is desired to place the balls on the table at the beginning of a game the said frame is placed exactly where it is desired to deposit the balls and the fingers or rods *b* are withdrawn and the balls drop onto the table in their proper position. Before placing the frame on the table the bottom surfaces of the balls, which are shown at *c*, project slightly below the bottom of said frame, as shown in Fig. 2, and when the frame is placed on the table the balls are slightly raised, as shown in Fig. 3, and do not rest on the fingers or rods *b*, and the withdrawal of said fingers or rods does not in any way interfere with the balls.

When the balls are in proper position in the frame, they are placed in transverse rows, as shown in Fig. 1, and in order for the fingers or rods *b* to support the balls in said frame there must be four of said fingers or rods, as is also shown in the drawings.

By means of my improvement I provide a frame, or, as it is usually called, a "triangle," in which the balls may be placed when they are taken from the pockets of the table and which may be supported on a rack or any other support and from which they may be deposited on the table in the exact position desired whenever necessary, and I thus avoid the necessity of providing other forms of supports or holders for the balls and at the same time provide means whereby the said balls may be properly positioned on the table at the beginning of the game without the necessity of sliding the triangle around over the cloth with which the table is provided.

Having fully described my invention, what I claim as new, and desire to secure by Letters Patent, is—

A device of the class described, comprising

UNITED STATES PATENT OFFICE.

PAUL JUSCHKE, OF NEW YORK, N. Y.

POOL-BALL PLACER AND HOLDER.

SPECIFICATION forming part of Letters Patent No. 752,292, dated February 16, 1904.

Application filed October 23, 1903. Serial No. 178,192. (No model.)

To all whom it may concern:

Be it known that I, PAUL JUSCHKE, a citizen of the United States, residing at New York, in the county of New York and State of New York, have invented certain new and useful Improvements in Pool-Ball Placers and Holders, of which the following is a specification, such as will enable those skilled in the art to which it appertains to make and use the same.

The object of this invention is to provide an improved device for holding pool-balls and for placing the same in proper position on a pool-table without the necessity of sliding the ordinary triangular holder over the table, and thus injuring the cloth with which the table is covered, a further object being to provide a triangular holder for pool-balls in which the latter may be placed when they are taken from the pockets and from which the said balls may be deposited in their proper position on the table; and with these and other objects in view the invention consists in a device of the class specified, constructed as hereinafter described and claimed.

The invention is fully disclosed in the following specification, of which the accompanying drawings form a part, in which the separate parts of my improvement are designated by suitable reference characters in each of the views, and in which—

Figure 1 is a plan view of a device embodying my invention; Fig. 2, a cross-section on the line 2-2 of Fig. 1; Fig. 3, a view similar to Fig. 2, but showing the balls in a different position; and Fig. 4, a view of a detail of the construction.

In the practice of my invention I provide a triangular frame *a* of the same form as those usually employed in placing pool-balls in proper position on a table, and the said triangular frame is provided in opposite sides thereof with holes *a*², through which are passed fingers or rods *b*, connected by a handpiece *b*². The fingers or rods *b* are preferably triangular in cross-section, as shown in Figs. 2 and 3, and the holes in the sides of the frame *a* are similarly formed.

The handpiece *b*² is preferably provided with a flange member *b*³, by which it may be ma-

nipulated, and in practice the rods or fingers *b* are passed through the triangular frame *a*, and in Fig. 1 of the drawings that part of the device represented by the fingers or rods *b* and the handpiece *b*² is shown partially withdrawn in full lines.

In practice the fingers or rods *b* are passed entirely through the triangular frame *a* and the balls are collected and placed in said frame and rest on said fingers or rods, and when it is desired to place the balls on the table at the beginning of a game the said frame is placed exactly where it is desired to deposit the balls and the fingers or rods *b* are withdrawn and the balls drop onto the table in their proper position. Before placing the frame on the table the bottom surfaces of the balls, which are shown at *c*, project slightly below the bottom of said frame, as shown in Fig. 2, and when the frame is placed on the table the balls are slightly raised, as shown in Fig. 3, and do not rest on the fingers or rods *b*, and the withdrawal of said fingers or rods does not in any way interfere with the balls.

When the balls are in proper position in the frame, they are placed in transverse rows, as shown in Fig. 1, and in order for the fingers or rods *b* to support the balls in said frame there must be four of said fingers or rods, as is also shown in the drawings.

By means of my improvement I provide a frame, or, as it is usually called, a "triangle," in which the balls may be placed when they are taken from the pockets of the table and which may be supported on a rack or any other support and from which they may be deposited on the table in the exact position desired whenever necessary, and I thus avoid the necessity of providing other forms of supports or holders for the balls and at the same time provide means whereby the said balls may be properly positioned on the table at the beginning of the game without the necessity of sliding the triangle around over the cloth with which the table is provided.

Having fully described my invention, what I claim as new, and desire to secure by Letters Patent, is—

A device of the class described, comprising
